UNITED STATES PATENT OFFICE

HARRY SWINGLEHURST, OF ORANGE, NEW JERSEY, ASSIGNOR TO SCOTT & WILLIAMS, INCORPORATED, OF NEW YORK, N. Y., A CORPORATION OF MASSACHUSETTS

KNITTING MACHINE

Application filed January 16, 1932. Serial No. 587,020.

This invention relates to knitting machines for producing fabrics having variations in stitch structure caused by transferring of loops, and more particularly the formation of eyelet holes in the fabric by transferring sinker wale loops to adjacent needle wales. The invention concerns more particularly circular knitting machines adapted to transfer sinker wale loops to adjoining wales, and the object of the invention is to decrease the length of yarn drawn in such transferred loops when making a fine gauge fabric.

The invention will be shown and described embodied in a Scott & Williams revolving cam cylinder knitting machine adapted to transfer sinker wales to adjacent needle wales by the use of transfer jacks. It will be understood that the invention is also applicable to machines in which the needle cylinder revolves. The particular machine shown is adapted to knit plain fabric, fabric in which eyelets are made by all the jacks consecutively, and/or fabric in which patterned eyelet fabric is formed by means of jack selection. According to this invention certain of the sinkers or web holders in the machine are nebless and the lower edges of the transfer jacks move at a level below the tops of the remaining nebs.

In the drawings,

Figure 1 is a vertical sectional view through one-half the dial and bedplate of a Scott & Williams revolving cam cylinder underwear machine embodying the invention, this view being taken through one of the jack pattern wheels approximately on the line L of Figure 3;

Figure 2 is a development of one quarter of the cam cylinder for the needles;

Figure 3 is a plan view from the underside of one quarter of the dial showing the path for the butts of the transfer jacks, this view being taken on the line 3—3 of Figure 1 and including a showing of two pattern wheels for causing selective formation of eyelet holes;

Figure 4 is a diagram in plan showing the relation of the transfer jacks, needles and

sinkers in the three principal positions of the transfer jacks;

Figure 5 is a perspective of a single transfer jack;

Figure 6 is a plan view showing the jack extended to transfer position with the sinker wale over its adjoining needle wale;

Figure 7 is a view in elevation of three sinkers and a transfer jack looking toward the center of the machine and showing the level at which the jack moves with relation to the loop-measuring ledges and the nebs of the sinkers;

Figure 8 is a perspective showing a transfer jack playing over the top of a nebless sinker;

Figure 9 is a similar perspective showing the jack contacting with the neb of an adjacent sinker;

Figure 10 is a perspective of a double transfer jack;

Figure 11 is a diagram in plan similar to Figure 4 showing the relation of the double transfer jacks of Figure 10 to the sinkers and the needles in the three principal positions of the transfer jack; while

Figure 12 is a side elevation of the new nebless sinker or web holder.

When making ornamental openwork effects by means of transferring loops laterally to form eyelet holes in the knitted web, the yarn is laid over the top of jacks in addition to the sinkers in order that those jacks may subsequently transfer those loops laterally. The resulting fabric is shown in the Robert W. Scott Patent No. 846,353, dated March 5, 1907, and transfer jacks of this general type are shown in the patent to Robert W. Scott No. 846,430, dated March 5, 1907.

When making fine-gauge fabric of this type, it is necessary to reduce to a minimum the length of stitch drawn, and in order that the stitch drawn over the nose of the transfer jack in such fine gauge machines may not be too long proportionately to other stitches, I propose to associate the sinkers, needles and web holders in the novel manner hereinafter described. In this arrangement the nose of each transfer jack lies above a sinker which has no neb

or web holding nose above its knocking-over or loop-measuring ledge. The jack is located down close to the knocking-over ledge of the sinker with its lower edge separated from the ledge by only enough space for the fabric to pass. Adjacent to the nebelless sinker preferably is a sinker having the usual nose or neb. The parts are assembled preferably in such a manner that the lateral bend of the transfer jack will be in sliding contact with the neb of the adjacent sinker. When it is desired to transfer a sinker wale laterally in one direction only, a single jack such as shown in Figure 5 may be employed, but if it is desired to transfer that sinker wale laterally to the needles on both sides, then a double transfer jack such as shown in Figure 10 may be employed.

Referring now to the general construction of the machine, the machine has a revolving central spindle 15 upon which is mounted a stationary dial 19 fastened to a sleeve 18, and a stationary bedplate 16 on which is mounted the needle cylinder 17. The revolving elements in the machine shown are the gear ring 21 and the cam cylinder 20 revolving therewith, the sinker cam cap 23 and the dial cam cap 24. The needle cylinder and dial are stationary. The sinkers or web holders 25, 26 are carried by the outside sinker ring 22 and the inside sinker ring 27 in the usual manner, the inside ring being supported by the upper end of the needle cylinder. The sinkers and needles are manipulated in the usual manner, the machine illustrated in the drawings being one in which sixteen courses are knit on each revolution of the machine. As already mentioned, the transfer jacks can be controlled to produce plain fabric without any eyelet holes at all, or eyelet holes at every jack, or an eyelet pattern in which only certain jacks cause the making of eyelets. In the particular form of the invention shown in the drawings, means are provided for transferring sinker wale loops from a plurality of courses at the one time, two yarns being fed and drawn before the transfer is made.

The single transfer jacks above referred to are designated generally by the numeral 28 and are carried on the dial verge 29 fastened on the upper face of the dial 19. These transfer jacks have an operating butt 36, a shank 31 and a lateral bend 32 which extends to one side of the main portion of the jack a distance corresponding to the distance between one sinker and its neighbor as they lie mounted in the machine (Figure 5). The forward or outer end of the jack forms the nose 30, its tip being in line with the shank 31 and the nose being the portion cut lower than the remainder of the jack and affording a shoulder 34 against which the sinker loop rests, as will be de-

scribed presently. It might be well at this point to note that a transfer jack has three primary radial positions, as shown in Figure 4, namely, the withdrawn or out-of-action position shown at the right of Figure 4, in which the outer end or nose 30 of the jack lies radially inward of the needles 37; the second position is with the end of the jack opposite the needles, the portion of the nose opposite the needles in this position being over the nebelless sinkers 26—this is the position in which the yarn is laid over the neb and the loop is drawn; the third primary position of the jack is the one shown at the left of Figure 4, in which the sinker loop has been transferred to a position above the adjacent needle wale and the portion of the transfer jack opposite the needle is the lateral bend 32, which lateral bend lies on the opposite side of the needle in question from the tip of the transfer jack. In this position the shoulder 34 of the jack is outside the circle of needles.

The mechanism for controlling the jacks will first be described and then the cam path for the needles will be described, the lettered lines of Figures 2 and 3 referring to corresponding points in the cam paths for the needles and jacks respectively. The cam path for the jacks includes fixed surfaces 41, 42, swivel cams 38, 40, 45, transfer cam 46 and pattern wheels generally designated by the reference characters 39 and 44 (Figure 3). Relatively to the cams the jacks move from left to right, as viewed in Figure 3, and the needles move from left to right, as viewed in Figure 2. When the jacks are at the point B they are extended fully to the transfer position shown at the left of Figure 4 and as they move past the point B they are pushed radially inward until by the time they reach point C they are out of action, with their tips slightly inside the circle of needles, as shown in the right-hand position of Figure 4. The next important move of the jacks is when they reach the swivel cam 38, the cam being shown in its retracted position. This swivel cam is used only when all the transfer jacks are to make eyelets in the fabric, i. e., what is known as "all-eyelet fabric". If all-eyelet fabric is being made the cam is turned radially outward, causing the jacks to start out at the point J and remain out until point U where the actual transfer begins. At the point L the butts of the jacks come opposite the first pattern wheel whose construction will be described in detail subsequently. The pattern wheel projects to laying position any jack which meets a tooth. If either all-eyelet fabric or a pattern eyelet fabric is to be made, the swivel cam 40, located just after the pattern wheel, will be retracted so as to permit the jack butts 36, which have been travelling in contact with the outer cam

edge 41 since leaving point J or which have just been projected radially by the pattern wheel generally designated by the number 39, to continue at that radial position in contact with the cam surface 42 which follows the swivel cam 40. The swivel cam 40 is solely for the purpose of pushing all the jacks radially inward in case any jacks have inadvertently moved to an outward position 10 when no eyelets are being made. The pattern wheel 39 and the swivel cam 38 act to press jacks outwardly only when so-called "two-course eyelets" are being formed, the stitches of the first course being knit at 15 point O just subsequent to the swivel cam 40. Immediately after point O, all transfer jacks not theretofore pushed out to the transfer position come in contact with a triangular cam piece 43 which serves to insure that all 20 the transfer jacks are ready to be selected by the second pattern wheel 44 acting at point Q. Pivotaly mounted just after the second pattern wheel 44 is another swivel cam 45 which insures that all jacks are retracted 25 when a plain course is to be made. This swivel cam is thrown outwardly to idle position if either an all-eyelet or an eyelet-pattern fabric is to be made. At point U all the jacks meet a transfer cam 46 which 30 pushes all the jacks radially outward for transfer of the sinker wale groups. When plain fabric is being made the transfer cam 46 can, if desired, be retracted to the position shown in dotted lines. After passing this 35 transfer cam the jacks meet an inclined surface similar to the incline at point B and are pulled radially inward, thus transferring their loops to the cylinder needles. At the end of that incline the jacks are out of action 40 in a position similar to that at point C and similar to the right-hand position shown in Figure 4. For the purpose of controlling the positions of the three swivel cams 38, 40 and 45, the cams are linked together by 45 means of arms similar in function to an arm 47 which is connected to a circular ring 48 set in the top of the dial cam cap 24. This ring 48 is adapted to be moved circumferentially relatively to the dial cam cap when- 50 ever a change in position of the swivel cams is needed. In the case of the swivel cams 40 and 45 forming part of the outer edge of the cam path, each of those swivel cams is connected to its arm 47 by a vertical pin 49 and the connections between the arms 47 and the ring 48 are swivelled by means of a pin 50 playing in the slot in the end of each arm 47, the pin 50 projecting upwardly from the surface of the ring 48 (see Figures 1 and 55 3). Swivel cam 38 is also connected to the ring 48 by means of an arm 47' intermeshed with a pin 49' on an extension 51 on the ring 48 (see Fig. 3). These three swivel cams are therefore linked together and move simultaneously. This linkage is such 60 that all three cams are radially inward of the machine at the same time when plain fabric with no eyelet holes is to be made, the swivel cam 38 being retracted out of contact with the butts of the jacks and the cams 40, 45 being radially inward into the paths of the butts so as to retract immediately any jacks which may be selected by the pattern wheels 39 and 44. Their radially outermost position is the one in which all-eyelet fab- 65 ric is produced and in this position the swivel cam 38 presses radially outward all transfer jacks while the swivel cams 40 and 45 are withdrawn out of the paths of the butts 36 of the jacks. When it is desired to pro- 70 duce an eyelet pattern by means of the pattern wheels 39 and 44, the three swivel cams are in an intermediate or neutral position in which the swivel cams allow the jacks to be selected by the pattern wheels, carried out 75 to take the yarn and to remain out until the transfer. The transfer cam 46, if desired, can be left out permanently in the operative position shown by the solid lines in Figure 80 3 because unless the jacks have been pushed radially outward by the pattern wheels or the swivel cams early enough to have yarn laid over them, the pushing out of the jacks at the transfer point will not cause the mak- 85 ing of eyelets. However, if desired, the transfer cam 46 can be made adjustable or retractable so as to withdraw the cam when plain fabric is to be made. The showing in Figure 3 constitutes one quarter of the 90 entire dial cap. 95

The pattern wheels 39, 44 are suspended from the dial cam cap 24 by means of a bracket 52 on which the central pins 53 of the two wheels are carried. These wheels each comprise a supporting plate 54, a cut pattern disk 55 mounted thereon and a threaded clamp or nut 56 holding the cut disk on the supporting plate. This cut disk has teeth projecting from the circumference thereof wherever it is desired to have an eyelet in the fabric and those teeth are of such a length that as the disk is revolving the teeth will contact with the butts 36 of the transfer jacks and push them out to the intermediate position shown in Figure 4 where the yarn being fed to the needles will be laid over the nose of the transfer jack. The central pin 53 of each wheel projects from the bottom of the bracket 52, and fastened thereto by means of a countersunk disk and screw, is a gear wheel 57 meshing with an internal gear ring 58 held between the dial 19 and the dial verge 29 by means of the screw 33 which holds the dial and verge together. It will be obvious that as the dial cam cap 24 revolves about the stationary dial the gear wheel 57 will be revolved and thus cause the pattern disk to turn, bringing 105 selections for the transfer jacks into opera- 110 tive position successively. 115

120

125

130

Referring now to the cam path for the butts of the needles 37, the four knitting points shown in the quarter section of the cam cylinder are designated by the letters 5 D, J, O and T. The points at which the needles are raised to clear their latches are designated by the letters B, G, M and R. The portion of the cam cylinder where the needles are lowered while the jacks are carrying their loops out for transfer from the loop laying position to the transfer position lies between the points marked U and V and the needles are put up to take the transferred loops from the jacks beginning 10 at point W, the actual transfer being completed between the points B and C of the following quarter of the cam cylinder.

The construction of the machine having been set forth, its operation will now be described. We shall first assume that plain fabric is being knit without any eyelet holes in it. In this case the ring 48 will be pushed to its extreme position in the direction of knitting, i. e., to the right in Figure 3, and 15 the swivel cam 38 will be withdrawn from the paths of the butts 36 of the transfer jacks while the swivel cams 40 and 45 are inserted into the paths of those butts, so that it will move radially inward any jacks which 20 may be selected by the pattern wheel. If the transfer cam 46 at the left hand of the section has not been withdrawn from operative position all of the jacks will be radially outward in transfer position at the point A 25 and in this case the needles clearing at the point B will come up beside the jacks, but by the time the elements have reached the point C where the new yarn is being fed to the needles, the jacks will have been retracted. At the point D plain stitches have 30 been drawn and are knit in, and at the point G the latches of the needles which are just cleared have new yarn fed immediately and knit in to make the second course of plain 35 stitches at point J. The jacks are not moved out at point J by the swivel cam 38 because that cam is retracted, but as the jacks pass the pattern wheel 39 at the point L any which may be selected by teeth on the pattern 40 wheel disk 55 will immediately thereafter be retracted at the point N before a yarn can be laid over them. At point O a third plain course is knit by the needles. At point Q the jacks are passing the second 45 pattern wheel 44 and some of them may be selected to move radially outward at this point. The needles clear their latches again at point R but before any yarns can be laid over the noses of any jacks which may have 50 been selected by the pattern wheel 44, the swivel cam 45 withdraws those jacks at point S and the fourth course of plain stitches is knit at point T. If the transfer cam 46 at the right hand of the quarter section, as shown in Figure 3, has been with-

drawn, the jacks remain in their retrieved or withdrawn position as they pass points U, V and W, but if the cam has been left in again the jacks are pushed radially outward and remain there until clearing point B on the following quarter section of the cam segment, plain fabric resulting in either case because the jacks have no yarn on their noses.

When it is desired to make fabric with simultaneous transfer of two sinker wale loops on each jack, the operation of the machine is as follows: The ring 48 is moved to its extreme left position, as shown in Figure 3, having the effect of advancing the swivel cam 38 into the path of the butts of the transfer jacks and retracting swivel cams 40 and 45 out of the path of those butts. The transfer cams 46 at the beginning and end of the quarter segment shown are in inserted position. The transfer jacks coming up to the point A have on them two sinker wale loops each and the transfer cam 46 forces them out to the transfer position, as shown at the left of Figure 4 and as shown in Figure 6. By the time the transfer jacks reach the point B the needles have been raised to the clearing point so that they project within the sinker wale loop and when at point C the jacks are retrieved or retired radially inward out of action behind the cylinder needles, the needles take the sinker wale loops and the transfer is complete. A new yarn is then fed to the needles and at point D the transferred loops and the new yarn are all knit in. A plain course is then knit, the needles clearing at point G and knitting at point J. At point J all the jacks are moved radially outward to their middle position where loops can be laid over them, but they come out too late to receive the yarn which is knit in at the point J. The pattern wheel 39 at the point L does not cause any change of position of the pattern jacks because that wheel is adapted to push the jacks outwardly to the loop-laying position and all the jacks are already in that position. The swivel cam 40 being retracted, the jacks pass that point without being moved. The yarn for the next or third course in the quarter segment as it is fed under the hooks of the needles lies over the noses of the jacks, the needles having cleared at the point M. At the point O the needles knit their first course over the jacks but the jacks remain out in their yarn-laying position and the machine continues its revolution past the second pattern wheel 44 and the second swivel cam 45, which are ineffective on the jacks for the same reasons that the first pattern wheel 39 and the first swivel cam 40 were ineffective, and the needles which were cleared at point R have yarn fed to them, a second sinker wale loop being laid over the jacks. The needles knit

at point T. Between the point T and the point U, the needles are raised and lowered again in order that the stitches thereon may open the latches and that the latches will not 5 get inside the transferred loops. This avoids breaking of the transferred loop or the regular loop on the needle. Between the point U and the point V the transfer cam 46 shown at the right of Figure 3 forces 10 all the transfer jacks out to the transfer position; and between point V and point W the needles are raised to take the transfer loops. The jacks are retrieved or withdrawn beginning at point B at the next quarter 15 segment of the machine, as already described with regard to points A, B and C at the beginning of the quarter segment. In this way a plurality of sinker wale loops have been accumulated and subsequently 20 transferred simultaneously in the one course.

If it is desired to have an eyelet pattern, i. e., to make eyelet holes on certain jacks only, the two pattern wheels 39 and 44 are 25 availed of to provide the necessary selection (Figure 3). In order not to nullify the action of those two pattern wheels the control ring 48 is moved circumferentially to its mid position, in which position the 30 three swivel cams 38, 40 and 45 are all in a neutral position where none of them interferes with jacks which are at the out-of-action or at the loop-laying position. When 35 making this type of fabric the transfer cams 46 will of course be in their operative or outward position and the transfer and knitting in of the sinker wale loops laid on the jacks in the previous quarter of the machine occur at points B, C and D, as in the case 40 of the all-eyelet fabric above described. The knitting of the plain course between point G and point J is also the same as heretofore. As already mentioned, the swivel cam 38 is not inserted far enough to move 45 the transfer jacks whose butts are riding along the path 35 at the idle position, and as the butts of the jacks come opposite the first selecting wheel 39 certain of them are pushed radially outward by teeth on the 50 pattern wheel to a position where their noses will underlie the yarn being fed to the needles between the points M and O. The sinker wale loops are therefore laid over the noses of those jacks only. The first 55 course containing the selected sinker wale loops for transfer knits at point O. At point Q the selections for the second course containing the sinker wale loops to be transferred are made on the second pattern wheel 60 44. At point R the needles are raised to the clearing point; and at point T that second course is knit in. The needles are then raised to open the latches as heretofore explained. Thereafter the needles are drawn 65 down again by the time they reach point U and at point U the jacks begin to move radially outward to the transfer point. This pushing out of the jacks is completed by the time they reach the point V and immediately the needles begin to rise so that they are up to take the transfer loops by the time the elements reach point W. The needles continue rising, as is the case between points A and B of the quarter segment shown in the drawings, and at point 70 D the jacks begin to retire as before. In this way a selected two-course eyelet pattern is made. It will be obvious that by leaving out entirely the disk 55 of the first wheel 39, one-course eyelets can be produced.

In knitting eyelet fabric of this general character when fine-gauge fabric is desired, the size of the normal stitch becomes so small that it is impossible to draw a sinker 85 wale loop over the nose of the transfer jack in the ordinary eyelet machine, which will not be so slack as to be robbed and produce a general looseness of the fabric on either side of the eyelet. I have discovered that the relative size of the sinker wale loop drawn over the nose of the transfer jack can be made sufficiently small for fine-gauge fabrics to avoid this robbing and produce the proper proportionate size of an 90 eyelet hole by locating the lower edge of the transfer jack at a level below the tops of the nebs of the sinkers, and in order to do this I propose to use certain sinkers with nebs 61 and certain others without nebs. The knocking over or loop-measuring ledge 62 of the nebless sinker 26 is on a level 95 with the similar ledge 62' of the ordinary sinker 25. I also prefer to locate my transfer jacks in such a manner that the lateral extensions thereof have a brushing contact 100 with the sinkers having nebs thereon, and to have the line of the shank and the tip of the transfer jack directly above the nebless sinker, leaving merely sufficient room 105 for fabric to play thereunder. It will be noted that the jacks move with their lower edges below the tops of the nebs and leaving only room enough for the passage 110 of fabric between the jack and the knocking over ledge. In this way the end or nose of the transfer jack is brought sufficiently low with regard to the regular knocking over ledges 62, 62' to provide sufficiently 115 small sinker wale loops when loops are drawn over the nose. This intercalation of needles, sinkers with nebs for holding down the fabric, other sinkers having no nebs above their loop-drawing ledges 62, and the transfer jacks located beside the nebs of the 120 neb sinkers and in lateral contact therewith, makes it possible to knit eyelet fabric of a very fine gauge with a uniformity of size 125 of stitch not otherwise obtainable.

It will be obvious that my invention may 130

be used in the transfer of a sinker wale loop laterally in two directions at the one time onto the adjacent needle on each side, and in such case a jack such as shown in Figure

- 5 10 may be employed. This jack comprises two elements 59 and 59', such as shown in Figure 5, with the lateral bend in one formed in the opposite direction from the other, and in order to keep the two halves of the jack 10 together in the same radial position at all times, the two halves are spotwelded together at the butts, as indicated in Figure 10 by the two dots 60 thereon, the two halves being shown as not otherwise fastened together. The operation of such a double transfer jack will be obvious in view of the description given of the single jack and the patents to Robert W. Scott Nos. 846,430, 846,431, both dated March 5, 1907, and 919,-

20 962, dated April 27, 1909.

If it is desired to control the groups of swivel cams in each quarter segment of the machine independently of the other groups the ring 48 is made in four pieces—one for 25 each quarter. Each piece then is shorter than its segment, as indicated by the dotted line at the left of Fig. 3. This permits such control of the ring pieces that their changes occur at the same point in the fabric.

20 What I claim is:—

1. In a knitting machine the combination of needles, loop-measuring sinkers associated therewith, some of said sinkers having nebs for holding down fabric loops and 35 others having no nebs, and jacks having lower edges adapted to move above said nebless sinkers and below the tops of adjacent nebs, said jacks being for the purpose of transferring sinker loops to adjoining 40 needles.

2. In a knitting machine the combination of needles, loop-measuring sinkers associated therewith, some of said sinkers having nebs for holding down knitted fabric and others 45 having no nebs, and jacks adapted to have loops drawn over them and moving beside nebbed sinkers and contacting therewith and above the level of the nebless sinkers, said jacks being adapted to transfer loops 50 on said jacks laterally to adjoining needles.

3. In a knitting machine a series of needles, and sinkers associated therewith having ledges for measuring loops, some of said sinkers having nebs for holding down fabric and others having no nebs, in combination with jacks adapted to move with their lower edges below the tops of the nebs and over the top of the nebless sinkers for the purpose of drawing loops above the nebless sinkers and transferring same laterally to adjoining needles.

4. In a knitting machine a series of needles, and sinkers associated therewith having ledges for measuring loops, some of said 65 sinkers having nebs located above their

ledges for holding down fabric and others having no nebs, in combination with jacks adapted to move above said nebless sinkers with their lower edges on a level between the ledges on said nebless sinkers and the tops of the nebs of the other sinkers, said jacks contacting laterally with nebbed sinkers and being adapted to transfer loops laterally to needles adjacent the nebless sinkers.

5. A circular knitting machine having a series of independent vertical needles, sinkers intercalated with said needles, some of said sinkers having nebs located above loop-measuring ledges thereon and others lacking said nebs, in combination with jacks having stems and lateral bends therein for the purpose of transferring loops to needles adjacent nebless sinkers, said jacks, needles and sinkers being associated in such manner that the lower edges of said jacks move radially at a level between the ledges on said nebless sinkers and the tops of the nebs of the other sinkers and the lateral bends in said jacks contact each with the neb of an adjacent nebbed sinker.

6. A circular knitting machine having a circular series of independent needles, sinkers having loop-measuring ledges and nebs thereabove intercalated with said needles, there being single sinkers without any loop-holding structure above the loop-measuring ledge located at intervals in the circle of needles, the adjacent sinkers being nebbed, in combination with a radially movable transfer jack corresponding to each nebless sinker and adapted to measure an abnormal wale and transfer same to an adjoining needle, said jacks having a lateral bend adapted to contact with the neb of an adjoining sinker when projected to transfer position, and the lower edges of said jacks being on a level with the loop-measuring ledges.

7. A knitting machine having needles, elements having loop-measuring ledges associated therewith, some of said associated elements having nebs and others lacking them, in combination with elements each located above a nebless loop-measuring element and adapted to transfer a loop drawn on it to an adjoining needle, the lower edge of said transferring element moving at a level opposite the nebs.

8. A knitting machine having needles, and sinkers having loop-measuring ledges intercalated with said needles, the highest point on some of the sinkers being below the highest point on other sinkers, in combination with means including a jack above one of the less high sinkers for transferring a loop drawn on it to an adjacent needle, the lower edge of said jack being below the highest point on the higher sinkers.

9. In a knitting machine the combination of needles, loop-measuring sinkers associated

therewith, some of said sinkers having nebs for holding down knitted fabric and others having no nebs, and jacks located above the nebless sinkers and moving beside the nebbed sinkers, said jacks being adapted to transfer laterally to adjoining needles loops drawn over them.

10. In a knitting machine a series of needles and loop-measuring sinkers associated therewith, there being single nebless sinkers intercalated between sinkers having nebs, in combination with transfer jacks each located above a nebless sinker, having stems and lateral bends in said stems, each jack being adapted to transfer laterally to an adjoining needle loops drawn on it and to move with its bend in contact with the side of the neb of an adjacent sinker.

11. In a knitting machine the combination of needles, nebless and nebbed loop-measuring sinkers intercalated and associated therewith, and a jack adapted to measure a loop above a nebless sinker and transfer same to an adjoining needle, said jack moving beside the neb of one of said sinkers.

12. In a knitting machine the combination of needles, nebless and nebbed loop-measuring sinkers intercalated and associated therewith, and a jack adapted to measure a loop above a nebless sinker and transfer same to an adjoining needle, said jack moving beside and in contact with the neb of one of said sinkers.

In testimony whereof I have signed my
35 name to this specification.

HARRY SWINGLEHURST.
